Primary Examiner — Patricia Palasik(74) *Attorney, Agent, or Firm* — Cozen O'Connor(57) **CLAIM**

We claim the ornamental design for a rotary damper, as shown and described.

DESCRIPTION

FIG. 1 is a front view of a rotary damper showing the new design;

FIG. 2 is a rear view of a rotary damper of FIG. 1;

FIG. 3 is a bottom view of a rotary damper of FIG. 1;

FIG. 4 is a left side view of a rotary damper of FIG. 1;

FIG. 5 is a right side view of a rotary damper of FIG. 1;

FIG. 6 is a plan view of a rotary damper of FIG. 1;

FIG. 7 is a cross-section A-A view of a rotary damper of FIG. 1; and,

FIG. 8 is a cross-section B-B view of a rotary damper of FIG. 1.

The broken lines shown in FIGS. 1-8 represent unclaimed portions of the claimed design of a rotary damper.
